UNITED STATES PATENT OFFICE.

RODOLPH C. BOWERS, OF CARLYLE, ILLINOIS.

FOLDING BED.

SPECIFICATION forming part of Letters Patent No. 376,851, dated January 24, 1888.

Application filed September 2, 1887. Serial No. 248,641. (No model.)

To all whom it may concern:

Be it known that I, RODOLPH C. BOWERS, a citizen of the United States, residing at Carlyle, in the county of Clinton and State of Illinois, have invented certain new and useful Improvements in Folding Beds; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to folding beds, chiefly of that class which when folded present the appearance of a wardrobe.

The object of the invention is to improve the counterpoise mechanism and render the 20 same simple and efficient, and to so dispose and proportion the parts that the force exerted by the counterpoise will be about equal, no matter what may be the position of the bed, whether closed or opened or at any point between these two positions.

25 The improvement consists in the novel and peculiar construction and arrangement of parts presently to be described and claimed, and shown in the annexed drawings, in which—

30 Figure 1 is a perspective view, parts being broken away, of a bed embodying my invention, showing the bed unfolded; Fig. 2, a perspective view showing the bed folded; and Fig. 3, a detail perspective view of the case 35 having the front removed, a portion of the bed, and the counterpoise mechanism, showing the relative position of the counterpoise mechanism when the bed is folded and unfolded by full and dotted lines, respectively.

40 The bed is of the usual construction and is composed of the head and foot sections, A and B, the side rails, C, and the bed-bottom D. The side rails near the head are widened, as at c, and the lower edges of these widened 45 portions are covered by the board E, which is suitably finished to give the appearance of a set of bureau-drawers. The shelf F, placed on the ends of the widened portions c, is secured thereto by hinges on the front of the widened 50 portions c, so that said shelf can be turned down, as shown by dotted lines in Fig. 2. The

space G² between the shelf F and the foot-section B is bordered by the side pieces, G, secured to the rails C, and the end piece, G', fastened to the foot-section B. The brackets 55 g, secured to the side pieces, G, have the glass H pivotally supported between them, the glass being adapted to swing in the space G².

The case or head-board I has a broad base, I', to give stability to the structure, and a hollow upper portion to inclose the counterpoise, which is composed of the levers J, extending in opposite directions and intersecting or crossing each other at a point midway between their ends and pivoted at their opposite ends 60 to the sides of the case. The weights K are suspended from the free ends of the levers, and the rod L is connected with the head of the bed and supports the levers at their point of crossing. This rod, as shown, is hinged to the 65 bed and is composed of three sections hinged together. The upper section is provided with a staple, i, in which rest the levers J. The bed is pivoted to the base of the case by the rod M, about which it turns when being folded 70 and unfolded.

The foot leg section, N, is hinged, by staples n, to the foot of the bed, and folds when the bed is folded, as shown in Fig. 2, and unfolds when the bed is let down, as shown in Fig. 1. 80 The cable-wire O, passing through opening b in the foot B, and connected at one end with the leg-section and at its other end with the arm m, extending from the rod M, is drawn taut by rotating said rod M, so as to draw said 85 leg-section up snug against the foot of the bed.

The staples n afford a loose connection between the leg-section and the foot B. Now, when the cable O is slack and the bed folded, the leg-section will turn down over the side 90 pieces, G, on each side of the glass H, as shown in Fig. 2. When the bed is unfolding, the leg-section will swing out and away from the side pieces, G, until the bed is completely unfolded, when the leg-section will occupy a vertical 95 position. By tightening the cable O the leg-section will be drawn up close to the foot B, as will be readily understood from Figs. 1 and 2 of the drawings.

When the bed is down, the levers J are in 100 approximately a horizontal position and the weights exert their utmost force to lift the bed,

be prevented. Then as the diaphragm cools and contracts the sides will return to their normal position and away from contact with the respective caps.

5 Instead of making the caps concave upon the inner side, they may be made flat, as indicated in Fig. 3, and the disks or sides of the diaphragm made concave, as represented in Fig. 3. In that case the same stop or support is given to the sides of the diaphragm under expansion.

The caps have a central opening, D, through them, by which a bearing may be attained directly upon the diaphragm, to utilize the expansion and contraction thereof.

15 The application of this diaphragm to a steam-trap is represented in Fig. 1, in which E represents an outer casing, F the lower head, and G the upper head, forming a chamber, in 20 which the diaphragm is set, as there represented. The lower side of the diaphragm rests upon a post, G', which extends through the opening in the lower cap of the diaphragm, and so that the lower side of the diaphragm, 25 will rest directly upon this post as a support.

At the upper side a similar post, H, is arranged through the opening D in the cap upon the upper side of the diaphragm, and so as to rest directly upon that side of the diaphragm.

30 The top G of the trap is provided with an opening, I, by which connection may be made directly with the steam-pipe, and opens into the trap, so that the contents of the steam-pipe may pass into the trap. The inner side of this opening forms a valve-seat, J, and to 35 the upper post, H, a valve, K, is applied, which is adapted to set upon the valve-seat J, so as to close the opening, but normally stands distant from the opening, and to an extent

40 within the limits of the expansion of the diaphragm, and so that as the diaphragm expands it will bring the valve to its seat and close that opening, or when the diaphragm is contracted it will open the valve, as represented in Fig. 1.

45 The lower end of the trap is provided with one or more holes, through which water may escape, and for convenience of adjustment the lower head is provided with a set-screw, L, by 50 which the diaphragm may be raised or lowered to increase or diminish the extent of opening of the valve.

The diaphragm and caps are constructed of somewhat less diameter than the casing, or so 55 as to leave sufficient space between the casing and the diaphragm for the water to pass below, as seen in Fig. 1.

This trap being applied so that the steam-pipe may communicate therewith in the usual 60 manner for opening steam-pipes to the trap, steam will pass into the trap through the opening J and cause the diaphragm to expand, and that expansion will immediately 65 close the trap, so as to prevent the further ad-

mission of steam; but the trap being exposed 65 to the atmosphere will cool the diaphragm and cause it to contract, open the valve, and permit whatever water may have accumulated in the pipe to flow therein until steam will again enter the trap and cause expansion 70 of the diaphragm to close the valve, the water passing off through the trap to waste.

In some cases a single expansible side of the diaphragm will be sufficient for practical purposes—say as seen in Fig. 4. In this case it 75 will be understood that the cap is only applied to the flexible side. I therefore wish to be understood as including the cap as applied to one or both sides of the diaphragm, accordingly as said sides are elastic or flexible, and 80 so as to leave a limited amount of space between the cap and its adjacent side of the diaphragm, and serve as a stop to limit the extent of movement of that side of the diaphragm.

85 This general application of the diaphragm to one steam-trap will be sufficient to enable others skilled in the art to apply it to other traps or to other purposes where a similar diaphragm is desired.

90 I claim—

1. The herein-described diaphragm for steam-traps and like purposes, consisting of a rigid wall, with one or both sides composed of elastic or flexible material, combined with 95 a cap corresponding to the respective elastic or flexible sides, secured to the rigid wall of the diaphragm, the said caps having an opening through them to the said elastic side or sides of the diaphragm, and the caps constructed to form a recess between their inner surface and the adjacent surface of the said sides of the diaphragm, substantially as described, and whereby said caps form stops to 100 limit the expansion of the said diaphragm.

105 2. A steam-trap consisting of a chamber, E, closed at its upper and lower ends, a diaphragm within said chamber, composed of a rigid wall with elastic or flexible top and bottom, with caps made fast to said diaphragm, 110 and so as to cover the said flexible or elastic sides, but leave a limited space between the inner surface of the caps and the adjacent surface of the sides of the diaphragm, the said caps having a central opening therein to said 115 sides of the diaphragm, a support, G', in the bottom of the diaphragm and upon which the lower side of the diaphragm rests, a valve supported on the upper side of said diaphragm through the cap, the upper end of the trap 120 provided with a valve-opening, which said valve on the diaphragm is adapted to open or close, substantially as described.
